UNITED STATES PATENT OFFICE

GEORGE E. WHITNEY, OF BRIDGEPORT, CONNECTICUT

UNDERFEED FURNACE

Application filed April 22, 1927, Serial No. 185,744. Renewed January 15, 1930.

This invention has reference to underfeed furnaces, in which the coal is automatically delivered to the fire pot at the bottom thereof and crowded or forced upwardly toward the top, but the invention particularly relates to the feeding of the coal and the simultaneous disposal of the ashes from the furnace.

The objects of the invention, which are prominently characteristic thereof, and which are present with others which will be apparent from the reading of the appended description, are as follows:

15 First,—to positively and continuously deliver the coal by means of an endless conveyor.

Second,—to remove the ashes automatically by the action of such conveyor on its return movement to the coal hopper.

Third,—to remove all possibility of deleterious action of the sulphuric acid, generated from wet coal, on the conveyor which is preferably made of iron.

Fourth,—to enable the conveyor to absorb heat from the ashes as well as from the fire pot, so that it will itself contribute heat units to the coal.

The coal is fed and delivered at the bottom of the fire pot by the action of an endless conveyor which is driven by means of 30 sprocket wheels that engage the conveyor, and the latter is composed of metallic links hinged together and carrying at suitable intervals pivoted members, which are herein-after termed pushers which latter move the 35 mass of coal forward toward the fire pot as the coal is delivered from the hopper, and this continuous pushing of the coal causes the latter to be forced upwardly within the fire pot so as to always keep up the proper supply 40 of coal.

As these pushers act against the coal, and also against the ashes, the inner portions of the pushers, which extend beyond the conveyor, are in abutment against elongated metallic keeper plates so that the pushers are held rigid when they are performing their functions, and when they are leaving the bottom of the fire pot or entering the bottom of 50 the coal hopper, provisions are made where-

by these pushers are swung downwardly so as to be out of the way.

The conveyor sections have lugs that engage with the teeth of the sprocket wheels, so that the latter may operate to positively effect the travel of the conveyor.

An electric motor is provided for revolving the sprocket wheels at a comparatively low speed, through intermediate gearing, and this motor also serves to operate a blower for 60 forcing air into a closed chamber that surrounds the fire pot and communicates with the latter through the medium of small perforations made in the walls of this pot, so that the combustion of the coal in the fire pot 65 is greatly facilitated by means of this air blast.

The fire pot is usually nearly filled with coal by the action of the feeding instrumentalities above referred to and a fire started in 70 the fire pot by charcoal, wood or other means, and the feeding of the coal temporarily discontinued and the blower operated. As soon as the fire is properly started in the coal the feeding of the latter is continued and the 75 blower may or may not be put in commission, its action being regulated by an ordinary butterfly valve, not shown in the drawings.

Coal is frequently wet, either when delivered, or else by the furnace tender himself 80 for the purpose of preventing dust, and when coal is wet the action of the steam or vapor generated within the fire pot will act on any sulphur which may be in the coal and will cause distillation of sulphuric acid which 85 gravitates and attacks the iron of the coal conveyor.

In instances, where the coal conveyor of underfeed furnaces has been stationary as to 90 lengthwise movement, that is to say, is permanently confined, this action of the sulphuric acid has completely destroyed the conveyor.

In the present invention the same defect 95 would undoubtedly be present, were it not for the fact that the conveyor is constantly traveling, and leaves the fire pot and passes into the open air and thence down through the warm ashes, and the action of the air, as an evaporator, coupled with the drying ef- 100

fects of the ashes and their heat, completely obviates all injurious effects of the acid.

Surrounding the fire pot and spaced therefrom is the ash pan for receiving the ashes as the latter are forced over the rim of the fire pot, and this pan has a conduit which leads downwardly immediately below the conveyor chain and extends throughout the length of the latter and delivers the ashes to any suitable receptacle such as an ash pit or can, or a suitable elevator for getting rid of the ashes. The final disposal of the ashes, however, has nothing to do with the present invention.

15 This preliminary description will aid in understanding the accompanying drawings which form a part of this application, and will be followed by a more detailed description referring specifically to these drawings by numerals of reference.

In the drawings

Figure 1 is a plan view.

Figure 2 is a side elevation, the ash pan being partly broken away.

25 Figure 3 is a section at the line 3—3 of Figure 1.

Figure 4 is a section at the line 4—4 of Figure 1.

Figure 5 is a section at the line 5—5 of Figure 1.

30 Figures 6 and 7 are sections at the line 6—6 of Figure 1 looking in reverse directions.

Figure 8 is a broken longitudinal section similar to Figure 3, and showing particularly the position of the pushers when entering the hopper and leaving the fire pot, and

Figure 9 is a fragmentary section showing one of the pushers immediately after entering the hopper.

40 1, 2, are the base members for sustaining the entire structure at each end thereof, 3 is the ash pan mounted on said supports, and 4, 5, are pairs of spaced brackets placed on said pan at each end of the structure, and riveted 45 to the supports thereby firmly fixing the ash pan thereto.

50 6, 7, are spaced cheek plates that are riveted to said brackets and are spanned by girders 8, 9, to which the fire pot 10 and coal hopper 11 are secured.

12 is an elongated track or guideway having at its sides depending flanges 13 that are riveted to the inside of the cheek plates 6 and 7 at the upper ends thereof, and 14 is a similar track or guideway having depending flanges 15 that are riveted to the inside of said cheek plates 6, 7, this conduit being intermediate guideways 12 and 14 forming abutments 60 against which the pushers engage so as to hold the latter firmly as will be presently explained.

Extending outwardly from the cheek plates 6 and 7, are ears 16, 17 (see Figure 3) within 65 which are journaled twin sprocket wheels 18,

19, by means of shafts 20, 21, keyed to the hubs 22, 23, of the sprocket wheels.

The coal conveyor is an endless chain, denoted generally by the numeral 24 and formed by links 25 hinged together at 26, each link having on its inner face at each side a lug 27 with which the sprocket wheels engage to drive the chain.

28 is a conduit formed by riveting a roof-like part 29 directly to the hopper and fire pot and also to the girders 8, 9, of the cheek plates 6, 7 this conduit being intermediate the hopper and fire pot.

At the outer end of the fire pot and hopper, openings 30, and 31, are provided, the floor of which is the upper track 12, the height and width of these openings being just sufficient to allow the passage of the chain, while the ends of this track at the middle portions thereof are cut away to provide notches, as shown at 32 and 33, the end wall 34 of the notch 33 being an abutment which passively functions to properly position the pushers after they have entered at the base of the hopper, as will be presently explained in detail.

25 The conduit 28 leads from the bottom of the hopper into the bottom of the fire pot, as is clearly shown at Figure 3, while the floor of the conduit is the track 12, and the bottom of the hopper has an elongated opening 35 of a width about equal to the width of the chain, the bottom 36 of the fire pot being provided with a similar opening 37.

38 are normally upstanding members carried by the chain and which impel the coal into the bottom of the fire pot, and these members will hereinafter be termed pushers.

40 These pushers 38 are quadrant shaped and are pivoted around hinged portions of the chain at suitable intervals, the width of the pushers being sufficient to impel coal into the fire pot, the pivotal points of the pushers being at the rectangular portions formed by the junction of the radial faces that form part of the quadrant shape of the pushers and when the buckets are in elevated position their bottoms rest on the stop 12, as shown at Figure 3 so that the pressure against the coal will have no effect on them. These pushers extend through openings 39 in the links 25, and when the pushers are swung rearwardly their circular backs 40 will pass close to the rear walls of said openings and the front faces of the buckets will lie flush with the links as in the instance of the pushers that are shown at Figure 8 as entering the hopper and leaving the fire pot.

45 Pre-supposing the parts to be in the position shown at Figure 3 with the sprocket wheels revolving, the pusher immediately outside the hopper will come in contact with the wall of the base of the hopper and will thereby be swung rearwardly and downwardly so that its front face will be substantially flush with the chain, and in this position the

pusher can enter the hopper, since the main portion of the pusher depends within the notch 33 in the track 12, and, as the chain advances, the pusher will strike the end wall 34, which will cause the pusher to right itself and assume normal position, as will be clearly understood by reference to Figure 8.

Also, as is shown at Figure 3, during the travel of the conveyor chain, the pusher that is within the bottom of the fire pot will strike the rear wall thereof, which will cause the pusher to swing rearwardly and downwardly into the notch 32 in the track 12 with its front face substantially flush with the chain, as clearly shown at Figure 8.

After the pushers leave the fire pot, as above explained, they are guided by the sprocket wheels 18 into a trough 41 which is a continuation of the ash pan 3, and immediately before entering the latter, the pushers, which, when they reach the bottom of the sprocket wheels, are in inverted position, as is shown at Figure 3, will strike the end of the track 14, which will cause them to assume normal position with their inner portions abutting said track, and during their travel they will shove the ashes in the trough and cause them to be emptied at the end of said trough. It is understood that the pusher members 38 being loosely pivoted, will assume by gravity a position whereby the same will pass beneath the lower track 14. However, in event that the pushers are held by friction in the position shown at the right of Fig. 3, same will be forced to their operative position by contacting with the forward end of track 14.

After the pushers have left the trough 41 they are carried around the sprocket wheels 19, as shown at Figure 3, and will successively pass within the hopper in the manner above set forth.

Coal placed within the hopper will be positively driven by the conveyor through the conduit 28 into the bottom of the fire pot, and this will cause the continuously delivered coal to be crowded upward within the pot, as is usual with underfeed furnaces.

The fact that an endless chain is employed which is provided with the lugs 27 that are engaged by the sprocket wheels, renders the feeding and delivery of the coal to the fire pot by the pushers absolutely positive, and this is a decided advantage possessed by my invention, and since the means which functions to this end is automatically put in inactive position for leaving the fire pot or for entering the hopper, and automatically re-established in operative position immediately after entering the hopper, and since such means on its return movement from the fire pot to the hopper operates to remove the ashes, the efficiency of my invention is greatly increased.

The description heretofore given refers

chiefly to the instrumentalities employed for feeding and delivering the coal from the hopper to the fire pot, and attention will now be called to the means utilized for revolving the sprocket wheels and supplying air to the mass of coal in the fire pot for combustion purposes, but, since such means consists of well known devices that are operated in the usual manner to bring about results that are quite ordinary, these devices have not been illustrated in detail, and they will merely be referred to generally.

42 is an angle plate which is fixed to one of the brackets 5 and supports an ordinary electric motor 43 whose shaft carries a worm 44 that is in mesh with a worm wheel 45 that is secured to the shaft 21 of the sprocket 19.

This worm has a very small diameter while the worm wheel is very large, so that it will be clear that the latter will be revolved very slowly.

The shaft of the motor also carries a blower fan (not shown), and after a fire is once started in the fire pot, the blower may be regulated to furnish very little air or the supply of the latter may be cut off entirely.

It will be observed that the sprocket wheels 19 are of a diameter greater than that of the sprocket wheels 18, and that the upper part of the conveyor declines downwardly toward the fire pot, while the lower part of this conveyor declines downwardly toward the sprocket wheels 19, and also that the abutments or tracks 12 and 14 are likewise declined, but these declinations merely contribute to the easy travel of the coal and ashes and are in no sense to be considered as limitations.

Heretofore, devices, such as screws, have been employed to feed the coal and deliver it to the fire pot, but it has frequently happened that the coal will hang to the screw and that the latter and also the coal will revolve without propelling the coal, and therefore such screw feed is not always reliable. Also, since the screw is stationary, except as to rotation, that part of the latter which is immediately below the fire pot has many times been eaten away by the sulphuric acid distilled from the coal.

In the present instance the feeding of the coal is positive, and the travel of the conveyor into the air beyond the fire pot, through the hot ashes, and again in the air, preparatory to entering the hopper, completely evaporates the acid and removes all traces of it.

Therefore, the gist of this invention, broadly speaking, lies in a continuously traveling conveyor which carries coal impelling members or pushers that are automatically positioned for service and for entering the hopper and leaving the fire pot.

The invention is not limited to the use of the ash removing feature, although the lat-

ter is desirable, since the ashes may be allowed to fall over the rim of the fire pot into any suitable receptacle.

What is claimed is:—

- 5 1. An apparatus of the character described, including a hopper and fire pot, a pair of tracks disposed beneath the hopper and fire pot and supported in spaced substantially parallel relation to each other, an endless conveyor movable on said tracks having a series of spaced pushers pivoted thereto, said tracks having contacting surfaces to engage the pushers so as to project and retain all thereof the same distance beyond said surfaces when in engagement therewith, and means to operate the conveyor and therewith the pushers. 75
- 10 2. In an underfeed furnace, a hopper, a fire pot, an ash pan surrounding the fire pot and having an extension providing a trough that extends beneath the furnace, an endless conveyor having continuous travel through said hopper, fire pot and trough and having a series of pivoted pushers carried thereby for impelling fuel or ashes, means to project 80
- 15 a portion of said pushers at substantially the same distance beyond the outer face of the conveyor during the performance of their several functions, means to position said pushers for entrance into the hopper and exit 85
- 20 from the fire pot and means for positioning said pushers for performing their fuel impelling functions after entering the hopper and for performing their ash removing functions after leaving the fire pot. 90
- 25 3. An apparatus of the character described including a hopper having a front wall and a fire pot having a rear wall, a track disposed beneath the hopper and fire pot and having its ends spaced from said walls, an endless conveyor composed of sections hinged together and having openings formed therethrough and having a series of spaced pushers carried thereby and mounted for swinging movement through the openings, said 100
- 30 pushers being engageable with the forward end of the track for movement to their operating position, the pushers being also engageable with the rear wall of the fire pot for movement to their inoperative position, 105
- 35 and means to actuate the conveyor. 110
- 40 4. An apparatus of the character described including a hopper and a fire pot, a track disposed beneath the hopper and fire pot, a second track beneath the first named track disposed in spaced substantially parallel relation thereto, an endless conveyor surrounding said tracks, and having a series of pivoted pushers carried thereby, said pushers each having a pair of angularly arranged faces, means to move one face of the pushers into engagement with the upper track so as to be supported against downward movement, said other face being engaged by the 120
- 45 lower track to be retained against upward 125
- 50 movement. 130

movement thereby, and means to actuate the conveyor.

In testimony whereof I affix my signature hereto.

GEORGE E. WHITNEY.
